UNITED STATES PATENT OFFICE.

ALFRED BREESE, OF LONDON, ENGLAND.

ADJUSTABLE BRACKET.

SPECIFICATION forming part of Letters Patent No. 768,929, dated August 30, 1904.

Application filed February 2, 1904. Serial No. 191,710. (No model.)

To all whom it may concern:

Be it known that I, ALFRED BREESE, a subject of the King of Great Britain and Ireland, residing at 75 Aldermanbury, in the city and county of London, England, have invented 5 certain new and useful Improvements in Adjustable Brackets, of which the following is a specification.

This invention relates to improvements in 10 adjustable brackets; and it has for its object the production of a bracket simple in form, easily and cheaply constructed, and effective in use for the various purposes for which brackets are employed.

15 In order that my said invention may be readily understood, reference is to be had to the following description and accompanying drawings, in which—

Figure 1 is a sectional view of my improved 20 bracket in its locked position. Fig. 2 is a plan view of the same. Fig. 3 is a sectional view of the bracket in its unlocked position ready for adjustment. Fig. 4 is a sectional view showing the slide and wedge or gripping 25 mechanism outside of the support. Figs. 5, 6, and 7 illustrate a modified form of outside gripping mechanism, and Fig. 8 shows a modified form of inside gripping mechanism.

Like letters of reference indicate 30 corresponding parts in the several views.

Referring first to Figs. 1 to 3, *a* represents the slide, adapted to slide inside a slotted support *b*. Pivoted at *c* in a slot *d* in said slide is an arm or bracket *e*, (pivoting in a direct 35 line *xx* with the central longitudinal axis of the arm,) having at its inner end a recess *f*, adapted to receive a wedge *g*, said wedge being either a ball, sphere, or block, in the present case taking the form of a ball or sphere. To 40 adjust the slide *a* at any desired position along the support *b*, the arm *e* is slightly tilted upward upon its pivot *c*, (see Fig. 3,) allowing the wedge to slightly recede into the recess or fork *f*, so that the slide *a* can now be slid 45 along the support *b*. To lock the slide when the desired position is attained, the arm *e* is moved down to the horizontal position or at right angles to the slide and support, thus raising and forcing the wedge *g* tightly against

the inner face *h* of the support *b*, and thereby 50 securely locking said slide.

Referring to Fig. 4, which illustrates my invention applied as an outside grip, the slide *a* is provided with forked jaws *ii*, (best shown in Fig. 6,) adapted to surround the support *b*, 55 the grip of the wedge *g* taking place on the face *j* of the support *b*.

In Figs. 5 to 7, which illustrate a modified form of outside grip, the wedge is in the form of a block having a recess *k*, adapted to be engaged by a knuckle *l* on the pivoted arm or bracket, its center with that of the pivot coinciding in a direct line with the central longitudinal axis *xx* of the arm *e*, the wedge *g* having its face *m* shaped to correspond with 60 the surface it is to engage. The method of unlocking the grip is the same as hereinbefore set forth—viz., an upward tilt of the bracket or arm *e*, causing the wedge to recede, as in Fig. 7, and to thereby free the slide. 70

While I have only in Figs. 5 to 7 shown the invention as applied to an outside grip, yet I may readily adapt the same for an inside grip, Figs. 1 to 3, as shown at Fig. 8, by altering the face *m* of the wedge *g* to conform to the 75 interior shape of the support, in which case I may reverse the positions of the knuckle *l* and recess *k* relatively to that shown in Figs. 5 to 7.

Although I have only shown and described the grip applied vertically, yet it is readily understood I may apply the same in a horizontal or any other position by modifying the shape of the slide and position of pivot without varying the relative "direct" positions of the pivot and wedge. 80

Having now described my invention, what I claim as new, and desire to secure by Letters Patent, is—

1. In an adjustable bracket, the combination, with a suitable support, of a slide movable vertically thereon, an arm pivoted near its inner end to said slide, and means interposed between the end of the arm and the adjacent face of a support permitting the arm to be raised and frictionally holding it when 95 brought to a horizontal position.

2. In an adjustable bracket, the combination, with a suitable support, of a slide mov-

able vertically thereon, an arm pivoted near its inner end to said slide, and a block having hinged connection with the inner end of the arm and adapted to bear against the adjacent 5 face of the support, thereby permitting the arm to be raised and frictionally holding it when brought to a horizontal position.

In testimony whereof I have affixed my signature in presence of two witnesses.

ALFRED BREESE.
